UNITED STATES PATENT OFFICE.

JOHN F. STANDISH, OF WINTHROP, MASSACHUSETTS, ASSIGNOR TO UNITED-XPEDITE FINISHING COMPANY, OF PORTLAND, MAINE, A CORPORATION OF MAINE.

RECEPTACLE FOR FINISHING-MACHINES.

1,353,860.

Specification of Letters Patent. Patented Sept. 28, 1920.

Application filed December 26, 1917. Serial No. 208,897.

To all whom it may concern:

Be it known that I, JOHN F. STANDISH, a citizen of the United States, residing at Winthrop, in the county of Suffolk and State of Massachusetts, have invented certain Improvements in Receptacles for Finishing-Machines, of which the following description, in connection with the accompanying drawings, is a specification, like reference characters on the drawings indicating like parts in the several figures.

My invention relates to receptacles for finishing machines and particularly to those adapted to supply finishing material for application to shoes. A specific instance of such receptacles is furnished by the wax pots employed for shoe burnishing machines.

In apparatus of the above character, it frequently becomes necessary for the operator in changing his work from shoes of one material to those of another to change also the finishing material, because, for example, of a difference in color. Moreover, shoes of different styles have heels varying widely in shape and require finishing tools of different dimensions and a consequent adjustment of the means for applying finishing material to the tools.

To meet such requirements a feature of this invention consists in the provision of means for so mounting a receptacle upon a finishing machine that it may be placed in position or removed with minimum effort and without disturbing other elements of the machine. In the embodiment illustrated this includes a readily separable connection between a movable applying member mounted in the receptacle and the driving mechanism therefor.

Another feature consists in supporting the receptacle for adjustment in a plurality of directions, these adjustments preferably being accomplished while the receptacle is maintained level so the contents shall not be caused to overflow.

Other features will be made evident by the following description and claims, taken in connection with the accompanying drawings illustrating a single embodiment of the invention, and in which—

Figure 1 is a front elevation of my improved receptacle associated with a heel-burnishing machine, a portion only of which is illustrated, and

Fig. 2 is a side elevation looking from the left in Fig. 1, parts being broken away.

At 10 appears a part of the frame of a burnishing machine for shoe heels and the like, this being the particular finishing apparatus in connection with which I have chosen to illustrate my invention. Journaled in the frame is a shaft 12 upon which is fixed a burnishing or finishing tool 14. Projecting from the frame below and parallel to the shaft of the burnishing tool is a horizontal spindle or supporting member 16, having a key-way connected by a key 18 with a hub or bracket 20 in which is a corresponding way to receive the key. This permits the bracket to be moved longitudinally of the spindle and prevents it from rotation thereon, the bracket being thus maintained in a fixed angular relation. To clamp the bracket in its adjusted position the hub which receives the spindle is divided, the portions being drawn together by a screw 22 extending through opposite bosses. Projecting rearwardly from the hub is a substantially horizontal arm 24 curved downwardly and outwardly from the machine frame to carry its extremity beyond the end of the spindle 16. In the upper face of the end of this arm is a horizontal way undercut at 26 to receive the dovetailed portion 28 formed at the bottom of a receptacle 30, which, in the present instance, is adapted to contain wax for burnishing and to maintain it in a fluid condition. The outer wall of the way or recess is furnished by a plate 32 overhanging the upper face of the bracket at 34 and secured to said bracket by a screw 36 extending through a vertical slot 38 in the plate. When this screw is loosened sufficiently to permit the overhang 34 of the plate to move away from the dovetailed base of the receptacle, the entire plate falls until the top of the slot 38 strikes the screws 36. This brings the portion 34 of the plate below the bottom of the way, allowing the receptacle to be withdrawn from the bracket in the direction of the axis of the spindle 16. To hold the plate 32 against turning upon the securing screw, it has at its lower extremity a slot 43 through which extends a pin 40 fixed in a depending portion 42 of the bracket. The slot 43 is of such length that the downward movement of the plate to free the receptacle is not interfered with.

Journaled in the wall of the receptacle is a shaft section 44 held against inward movement with respect to the receptacle by an annular flange 46 upon its outer end. At 5 the inner end of this shaft section, secured by a screw 47, is an applying member in the form of a wheel 48. The inner face of this wheel contacts with a wall of the receptacle, while it extends far enough above 10 said wall to permit its periphery to come into coöperation with the burnishing member 14. Its lower portion is immersed within the wax or other finishing material in the receptacle. The shaft section 44 is hollow 15 to receive a second shaft section 50, the latter having a pin or projection 52 engaging a recess 54 in the flange 46. In addition to its bearing in the shaft section 44 the section 50 is journaled in an arm 56 of the 20 bracket 20, this arm extending upwardly above the horizontal arm 24. The opening in the arm 56 which furnishes the bearing for the shaft section 50 is in the form of a horizontal slot 58, this allowing the movement 25 of adjustment of the receptacle in the way between the walls 26 and 34. The shaft section 50 is held in a longitudinally fixed relation to the arm 56 by a collar 60, pinned to the shaft at the outer side of the arm, 30 and by a portion of a universal joint 62 of the gimbal type which is secured to and holds the shaft section 50 against outward movement through the arm 56. By this arrangement of the shaft sections, when the 35 plate 32 is loosened and the receptacle withdrawn from the support the shaft sections 44 and 50 separate by a rectilinear movement, the section 50 being left supported in the slot in the arm 56.

40 The wax wheel 48 may be rotated from a suitably driven gear 64, journaled upon the frame of the machine, through a longitudinally movable shaft 66, a second universal joint 68 and a friction connection between 45 the two universal joints 62 and 68. The gear 64 is splined to the shaft at 72, thus permitting the shaft to be moved longitudinally while compelling its rotation with the gear. This, with the universal joints, provides for the free adjustment of the receptacle through the movement of its bracket upon the spindle and its own movement upon the bracket. The friction connection is shown as including a hollow split shaft 50 section 74 projecting from the universal joint 62, into which extends a shaft section 76 fixed to an element of the universal joint 68. To hold these two sections 74 and 76 in proper frictional engagement a ring 78 55 may be sprung about the split portion of the section 74. This connection offers sufficient resistance to slipping to allow the wheel 48 to be driven from the gear 64 when the wax is in a properly fluid condition, but if, as 60 at the time of starting, the wax has solidi-

fied, the sections may slip, thus preventing injury to the driving mechanism.

Upon the outer extremity of the arm 24 is pivoted at 80 a hood or shield 82 which completely incloses the receptacle and also 70 the burnishing member, except at the front where the operator applies the work. To properly position the hood in its angular relation to the parts protected, a screw 84 is threaded through a portion of the hood wall 75 and contacts with the machine frame. When the hood is swung outwardly upon its pivot the burnishing member and receptacle are entirely freed for access by the operator. At this time the receptacle may 80 be removed and a new one substituted, or it may be adjusted either longitudinally of the burnishing member upon the spindle 16 or toward and from said member upon the bracket. In the first-mentioned adjustment 85 the hood moves with the receptacle, the relation of the two elements with respect to one another remaining unchanged. The transverse width of the hood is sufficient to enable the second adjustment to be made 90 without interfering with the burnishing tool. For the adjustment of the receptacle upon the bracket the depth of the hood from front to rear of the machine is also such that the elements do not come into contact. 95 The hood is recessed at 86 and in the horizontal portion of the wall thus formed is an opening 88 over the top of the receptacle. Through this opening the operator may inspect the contents of the receptacle, may 100 take a portion therefrom for use in the work or may insert a fresh supply. I have shown upon the outer end face of the hood a gas pipe 90 secured by straps 92, 92 and joined to a source of supply by a flexible section 105 94. The outlet portion of the pipe extends through the opening 96 in the hood opposite the side of the burnishing tool, this opening being elongated so that the pipe may be adjusted through the securing straps 110 to properly apply the flame to heat tools of different diameters.

From what has been said, it will be seen that by loosening the screw 22 the receptacle of this invention may be adjusted into 115 position along the spindle 16 to bring the periphery of the wax-applying wheel 48 into coöperation with the burnishing tool at any desired point longitudinally, while slackening the engagement of the wall 32 with the 120 base of the receptacle permits the latter to be moved toward and from the burnishing tool, to provide for the use of tools of different diameters. The extensible character and universal pivoting of the connections 125 between the applying wheel and the driving member freely allows this, no appreciable resistance being offered to the adjustment by any part of the connections. Both movements of the receptacle are entirely in a 130

horizontal direction, so that its inclination is not disturbed and there is no danger of the contents being spilled, no matter how full the receptacle may be. As the hood 5 moves with the receptacle in its adjustment along the tool, the relation of the opening 88 to the receptacle is not thereby altered. When the receptacle is to be removed, a loosening of the screw 36 allows the wall 10 32 to fall from its engagement with the dovetailed base 28, whereupon the receptacle may be drawn outwardly in a straight line, separating the shaft sections 44 and 50 without special manipulation of the driving 15 connections and without interference with other portions of the machine. The section 50 is left supported by the arm 56 in a convenient position for reassembling.

Having thus described my invention, what 20 I claim as new and desire to secure by Letters Patent of the United States is:

1. In a finishing machine, the combination with a support provided with a recess having a separable wall section, of a receptacle 25 seated in the recess, and securing means for the wall section permitting it to be removed to free the receptacle from the recess. 2. In a finishing machine, the combination with a support provided with a guideway 30 one side of which is separable, of a receptacle mounted in the guideway, and securing means for the side of the guideway whereby said side may be readily separated to free the receptacle. 3. In a finishing machine, a receptacle 35 provided with a dovetailed projection, a way having a wall undercut to receive one side of the projection, and a separable securing member having a portion overhanging the 40 other side of the projection.

4. The combination with the frame of a finishing machine, of an arm projecting therefrom and being provided at its extremity with a way, a receptacle seated in 45 the way, and a retaining member separably secured to the outer end of the arm and cooperating with the receptacle.

5. In a finishing machine, the combination with a support, of a receptacle mounted 50 thereon, a retaining member for the receptacle, and securing means for the retaining member, the retaining member being constructed and arranged to move out of the path of the receptacle upon loosening the 55 securing means.

6. In a finishing machine, the combination with a support, of a receptacle mounted thereon, a retaining member for the receptacle, and securing means for the retaining 60 member, the retaining member being constructed and arranged to move out of the path of the receptacle upon loosening the securing means while remaining in cooperation with the securing means.

65 7. In a finishing machine, the combination

with a support, of a receptacle mounted thereon, a retaining member for the receptacle provided with a slot, and securing means for the retaining member extending through the slot, the retaining member being 70 arranged to fall clear of the receptacle upon loosening the securing means.

8. In a finishing machine, the combination with a support provided with a recess having a separable wall section which is provided with a slot, a screw passing through the slot and engaging the support, and a receptacle seated in the recess. 75

9. The combination with a finishing machine, of a receptacle, a driven member movable in the receptacle, readily separable means for securing the receptacle to the machine and upon separation permitting the removal of the receptacle in a definite direction, a driving member mounted upon the machine, and a separable connection between the driven member and driving member, the separation of the connection being effected by the removal of the receptacle. 80

10. The combination with a finishing machine, of a receptacle for finishing material, a rotatable applying member journaled in the receptacle, a driving member mounted upon the machine, and connections between the applying member and driving member 95 including a tubular shaft section, a shaft section entering said tubular section, and means for positively joining the sections for rotation.

11. The combination with a finishing machine, of a receptacle for finishing material, a rotatable applying member journaled in the receptacle, a driving member mounted upon the machine, and connections between the applying member and driving member 105 including a tubular shaft section and a shaft section entering said tubular section, said shaft sections having a co-operating projection and depression.

12. The combination with a finishing machine, of a receptacle for finishing material, a material-applying member movable in the receptacle, readily separable means for securing the receptacle to the machine, a driving member mounted upon the machine, and connections between the applying and driving members including a readily 115 separable portion and a frictional driving portion.

13. The combination with the frame of a finishing machine, of a receptacle for finishing material, a rotatable applying member journaled in the receptacle, a driving member mounted upon the machine, a shaft having separable sections connected to the applying member and driving member respectively, a bearing for one section carried by the receptacle, and a bearing for the other section fixed to the machine frame. 120 125

14. The combination with the frame of a 130

- finishing machine, of a bracket having a plurality of arms, a receptacle for finishing material carried by one arm, a movable applying member mounted upon the receptacle, 5 a driving member mounted upon the machine frame, and connections between the applying member and driving member supported by another arm of the bracket.
15. The combination with the frame of a finishing machine, of a bracket having a plurality of arms, a receptacle for finishing material carried by one arm, a shaft section 10 rotatable upon the receptacle, an applying member carried by said shaft section, a driving member mounted upon the machine frame, and a shaft section for coöperation 15 with the first-named shaft section journaled in another bracket arm and being connected with the driving member.
20. 16. In a finishing machine, a bracket having a generally horizontally extending arm and an upwardly extending arm, a receptacle mounted upon the horizontal arm, a rotatable applying member carried by the receptacle, and operating means for the applying member having a bearing in the upwardly extending arm adjacent to the receptacle.
30. 17. In a finishing machine, a finishing member, and a receptacle for finishing material arranged for movement during the operation of the machine toward and from the finishing member and transversely thereof.
35. 18. In a finishing machine, a finishing member, a receptacle for finishing material arranged for movement with respect to the finishing member in a plurality of angularly related directions, and means for preventing variation in the inclination of the receptacle during its movement.
45. 19. In a finishing machine, a horizontal support, a bracket mounted for horizontal movement upon the support during the operation of the machine, means to prevent tilting of the bracket upon the support during the movement of the bracket, and a receptacle for finishing material movable upon the bracket.
50. 20. In a finishing machine, a horizontal support, a bracket mounted for movement upon the support, and a receptacle for finishing material movable upon the bracket in a direction substantially at right angles to that of the movement of the bracket upon the support, both the bracket and receptacle being capable of movement during the operation of the machine.
60. 21. In a finishing machine, a horizontal support, a bracket mounted for movement upon the support, a receptacle for finishing material movable upon the bracket, and means for preventing angular movement of the bracket upon the support, while permitting longitudinal movement thereon.
22. In a finishing machine, a finishing member, a receptacle for finishing material arranged for movement with respect to the finishing member horizontally in a plurality of directions, a movable applying member 70 coöperating with the receptacle and finishing member, a driving member, and connections between the applying member and driving member permitting a universal movement of the applying member.
23. In a finishing machine, a finishing member, a receptacle for finishing material movable in a plurality of directions, a movable applying member mounted upon the receptacle and coöperating with the finishing member, a driving member, and connections between the applying member and driving member permitting a universal movement of the applying member.
24. In a finishing machine, a finishing 85 member, a receptacle for finishing material mounted for movement with respect to the finishing member, a rotatable applying member mounted upon the receptacle and coöperating with the finishing member, a rotatable driving member, a shaft connected to the driving member to rotate therewith and move longitudinally therethrough, and a universal connection between the shaft and the applying member.
25. In a finishing machine, a finishing member, a receptacle for finishing material mounted for movement with respect to the finishing member, a rotatable applying member mounted upon the receptacle and 90 coöperating with the finishing member, a rotatable driving member, a shaft connected to the driving member to rotate therewith and move longitudinally therethrough, and a frictional connection between the shaft and 100 the applying member.
26. In a finishing machine, a finishing member, a receptacle for finishing material mounted for movement with respect to the finishing member, a rotatable applying member mounted upon the receptacle and coöperating with the finishing member, a rotatable driving member, a shaft connected to the driving member to rotate therewith and move longitudinally therethrough, two 110 universal joints connecting the shaft and applying member, and a frictional connection between the universal joints.
27. In a finishing machine, a finishing member, a support movable with respect to the finishing member, a receptacle mounted upon the support, means for transferring finishing material from the receptacle to the finishing member, and a hood carried by the support and extending over the finishing member and receptacle.
28. In a finishing machine, a finishing member, a support movable with respect to the finishing member, a receptacle mounted upon the support, and a hood carried by the 120 support and receptacle.
65. 29. In a finishing machine, a finishing member, a support movable with respect to the finishing member, a receptacle mounted upon the support, means for transferring finishing material from the receptacle to the finishing member, and a hood carried by the support and receptacle.

support and extending over the finishing member and receptacle but being open at the front to give access to said finishing member, said hood being also provided with

5 an opening at the rear above the receptacle.

29. In a finishing machine, a finishing member, a support movable with respect to the finishing member, a receptacle mounted upon the support, and a hood pivoted upon

10 the support at a point below the receptacle and being movable to assume a position over the finishing member and receptacle or clear thereof.

30. The combination with the frame of a

15 finishing machine, of a finishing member

mounted thereon, a spindle projecting from the frame, a bracket movable upon the spindle, a receptacle for finishing material carried by the bracket, and a hood pivoted upon the bracket and extending over the

20 receptacle and finishing member.

31. In a finishing machine, a finishing member, a support movable with respect to the finishing member, a receptacle separably mounted upon the support, and a hood piv- 25

oted upon the support and coöperating with the receptacle.

In testimony whereof I have signed my name to this specification.

JOHN F. STANDISH.
